EXPANSIBLE LINK CHAIN FOR A WRIST- BAND OR SIMILAR ARTICLE

Alfred Pinson, Stamford, Conn., assignor to Apex
Accessories Co., Inc., Greenwich, Conn.

Application February 27, 1953, Serial No. 23,817

Term of patent 14 years

(Cl. D45—4)

To all whom it may concern:

Be it known that I, Alfred Pinson, a citizen of the United States, residing at Stamford, in Fairfield County, State of Connecticut, have invented a new, original, and ornamental Design for an Expansible Link Chain for a Wrist Band or Similar Article, of which the following is a specification, reference being had to the accompanying drawing forming part thereof.

Fig. 1 is a plan view of an expansible link chain showing my new design, the conventional bottom link being shown in broken lines;

Fig. 2 is a side elevational view thereof;

Fig. 3 is an end elevational view of one of the centralized top links of Fig. 1; and

Fig. 4 is an end elevational view of one of the bordering top links of Fig. 1.

I claim:

The ornamental design for an expansible link chain for a wrist band or similar article, as shown and described.

ALFRED PINSON.
